UNITED STATES PATENT OFFICE.

ARTHUR P. STRONG, OF CHICAGO, ILLINOIS.

FORCED-DRAFT STOKER.

Application filed January 24, 1923. Serial No. 614,515.

This invention relates to forced draft stokers of the type wherein the draft is supplied to the active grate surface from below and through a plurality of transverse compartments.

One object of my invention is to supply the draft to the several compartments from one end of the stoker, and thus avoid the use of side ducts as heretofore.

Another object of my invention is to introduce the draft into one compartment and supply the others from that compartment.

The invention consists further in the matters hereinafter described and more particularly set forth in the appended claims.

In the accompanying drawings—

Fig. 1 is a vertical longitudinal sectional view through a chain grate stoker constructed in accordance with my invention;

Fig. 2 is a transverse sectional view taken on line 2—2 of Fig. 1;

Fig. 3 is a fragmentary horizontal sectional view taken on line 3—3 of Fig. 1; and

Fig. 4 is a view of one of the damper plates for one of the compartments and taken on line 4—4 of Fig. 1.

In the drawings, 1 indicates an endless chain grate operating over drums 2, 2 at the ends of the same in accordance with the usual practice. The space between the upper and lower leads 3, 4 of the grate is divided into a plurality of draft compartments 5, 5 by a plurality of transverse members or beams 6, 6. The members 6, 6 are vertically arranged and are laterally spaced apart, as shown in Fig. 1, to provide the compartments. The upper lead 3 rests on skids or rails 7, 7 extending longitudinally of the grate and across the several members 6, 6.

The spaces between the skids 7 along the upper ends of the beams 6, 6 are closed by shoes 8. These make air seals for the various compartments 5, 5 along the upper edges of the members 6, 6. The latter terminate short of the lower lead 4, and to close the spaces thus provided I provide a number of shoes 9, 9. These have pivotal connection with the members 6, 6 so as to permit droppage carried by the lower lead 4 to pass thereunder toward the front of the grate.

The lower lead runs on skids or rails 10 supported by transverse channels 11, as shown in Fig. 1. There is a droppage collecting plate 12 beneath the skids 10 and

below the lower lead 4, as shown. Shoes 13 are arranged between the skids 10 in vertical alignment with the members 6 to make air seals under the lower lead 4 at the sides of the compartments 5. The members 6 extend to and are secured to or otherwise supported by vertical side plates 14, 14 at the sides of the stoker, as shown in Figs. 2 and 3. These plates 14 close the ends of the compartments 5 and extend up to the ledge plates 15, which not only support the sides of the upper lead 3, but also seal the compartments along the upper edges of the plates 14.

To supply the several compartments 5 with forced draft in accordance with my invention, I provide in front of the first compartment at the forward end of the stoker a main supply head 16. This is supported by the forwardly projecting side webs 17 on the front wall 18 and open through said webs to permit draft supply devices to be connected with said header. Extending through the first compartment 5 is a plurality of air conduits 19, 19. These open into the main air box or header 16 at their front ends and terminate at their rear ends at the transverse member 6 dividing the first compartment 5 from the second one. In extending through the first compartment, the conduits 19 pass through the forward upright member 6 of said first compartment, as shown.

The conduits 19 are preferably triangular in cross section, as shown in Fig. 2, and are arranged with their inclined walls uppermost to shed droppage on the lower lead 4. These conduits 19 open into the second compartment 5 through openings 20 provided for that purpose in the associated upright member 6. These openings 20 have the same shape as the conduits 19 so as to register with them.

It is the second compartment 5 that receives the draft at highest pressure, and to that end the conduits 19 open directly into it, as shown. The other compartments 5 do not need draft at the high pressure required for the second compartment and therefore may be supplied with draft from the second compartment.

To accomplish this, I provide in the member 6 dividing the first compartment from the second one, a plurality of draft openings 21, 21. To control the supplying of draft from the second compartment to the first,

I provide a damper plate 22 slidably supported on the inner side of said member 6 by suitably shaped bars 23, 23. The plate 22 is provided with a plurality of openings 24, 24^a of the same size and shape as the openings 20, 21 and arranged so as to be brought into and out of register with the latter in sliding the plate back and forth. To slide the plate 22, I provide at one side 10 of the stoker a link 25. This extends through the adjacent side wall 26 of the furnace setting and has pivotal connection at its inner end with the plate 22 and pivotal and slotted connection at its outer end with 15 an operating hand lever 27 outside of said wall.

To control the supply of draft to the compartments to the rear of the second one, I provide the members 6 of such compartments 20 with a plurality of draft openings 28, 28. These in each of said members 6 are controlled by plates 29, 29 slidably mounted on the associated member 6 by bars 30, 30, as shown. The plates 29 are each provided 25 with a plurality of openings 31, 31 of the same size and shape as the openings 28 and arranged so as to register with the latter by the movement of the plate 29. These plates 29 are also given movement from one 30 side of the stoker and for that purpose I have provided links 32 pivoted at their inner ends to the plates 29 and at their outer ends to hand levers 33 on the outside of the wall 26. These links 32 extend through the 35 wall in the same manner as the links 25.

By the structure shown and described, the use of vertical conduits at the sides of the stoker to supply draft to the several transverse compartments, as heretofore, is 40 avoided, and the draft supplied to the several compartments from a main one. The latter is usually the second compartment from the front of the stoker, inasmuch as the fuel layer over that compartment is that part of 45 the fuel bed which requires a high pressure draft to gain the ignition required in the operation of the stoker. The other compartments do not require draft of such high pressure, and by my invention such other compartments are supplied with draft from 50 the main one. The damper plates 22, 29 allow the draft supplied to the various compartments to be controlled, thus enabling the amount of draft supplied to the various compartments to be regulated to suit the combustion requirements on the various sections 55 of the grate. The transverse beams 6, 6 divide the compartments 5, 5 from one another and are the partition members thereof, 60 while the draft openings 21 and 28 constitute means placing the compartments in communication with each other.

While I have shown and described herein in detail a stoker construction embodying 65 the features of my invention, it is of course

to be understood that the details of construction and arrangement of parts illustrated may be variously changed and modified without departing from the spirit and scope of my invention.

70

I claim as my invention:

1. In a forced draft stoker, the combination with an endless chain grate, of means between the upper and lower grate leads providing a plurality of separate draft compartments opening upward toward the upper lead and downward toward the lower lead so that the latter may carry droppage from the compartments, said compartments having communication whereby forced draft 75 may be supplied to all compartments from one of the same, and means whereby said draft may be initially supplied to one of said compartments.

75

2. In a forced draft stoker, the combination with an endless chain grate, of spaced partition members between the upper and lower grate leads forming a plurality of separate draft compartments opening upward toward the upper lead and downward toward the lower lead so that the latter may carry droppage from the compartments, said partition members having openings permitting forced draft to be supplied to all 80 the compartments from one of the same, and means at the front of the stoker whereby said draft may be initially supplied to one of said compartments.

85

3. In a forced draft stoker, the combination with an endless chain grate, of means between the upper and lower grate leads forming a plurality of separate draft compartments opening upward toward the upper lead and downward toward the lower lead so that the latter may carry droppage from the 90 compartments, said compartments having communication whereby forced draft may be supplied to all the compartments from one of the same, and a draft supply conduit between said grate leads at the front of the 95 stoker and opening into the second compartment by extending through the first one.

100

4. In a forced draft stoker, the combination with an endless chain grate, of spaced partition members between the upper and lower grate leads forming a plurality of separate draft compartments opening upward toward the upper lead and downward toward the lower lead so that the latter may carry droppage from the compartments, said 110 partition members extending transversely across the grate and having damper controlled openings permitting forced draft to be supplied to all of the compartments from one of the same, means providing air seals for the compartments between the grate leads and said members, the air seal means along the lower edges of said members being pivoted shoes bearing against the lower lead, and means whereby forced draft may 120

115

125

130

be initially supplied to one of said compartments.

5. In a forced draft stoker, the combination with an endless chain grate, of spaced partition members between the upper and lower grate leads, forming a plurality of separate draft compartments closed at their ends, said compartments opening upward toward the upper lead and downward toward the lower lead so that the latter may carry droppage from the compartments, said partition members extending transversely across the grate, a main supply air box between the grate leads in front of the first compartment, and air conduits leading from said air box through the first compartment and opening into the second compartment through the partition member between the two, said compartments having communication with each other through the partition members.

6. In a forced draft stoker, the combination with an endless chain grate, of a plurality of spaced partition members between the upper and lower grate leads forming a plurality of separate draft compartments opening upward toward the upper lead and downward toward the lower lead so that the latter may carry droppage from the compartments, said partition members extending transversely across the grate and having draft openings, means for controlling the passage of draft through said openings, a main supply air box between the grate leads in front of the first compartment, and air ducts extending from said air box through the first compartment and opening into the second through the partition member between the two, said ducts having inclined top walls.

7. In a forced draft stoker, the combination with an endless chain grate, of spaced

partition members between the upper and lower grate leads forming a plurality of separate draft compartments opening upward toward the upper lead and downward toward the lower lead so that the latter may carry droppage from the compartments, said partition members extending transversely across the grate and provided with a plurality of draft openings, damper plates slidably mounted on said partition members and having openings therein for co-operation with the openings in the partition members for controlling the passage of draft therethrough, and means whereby forced draft may be supplied to one of said compartments.

8. In a forced draft stoker, the combination with an endless chain grate, of spaced partition members between the upper and lower grate leads forming a plurality of separate draft compartments opening upward toward the upper lead and downward toward the lower lead so that the latter may carry droppage from the compartments, said partition members extending transversely across the grate and having a plurality of draft openings therein, damper plates slidably mounted on the partition members and provided with openings for co-operation with the openings in the partition members for controlling the passage of draft therethrough, an air box between the grate leads and in front of the first compartment, and a plurality of air ducts leading from said box to the second compartment by extending through the first compartment, the damper plates of the second compartment having enlarged openings for said ducts.

In testimony that I claim the foregoing as my invention, I affix my signature this 20th day of January, A. D. 1923.

ARTHUR P. STRONG.
